UNITED STATES PATENT OFFICE

HUGO BRUCKNER, OF VIENNA, AUSTRIA

LIGHT-REFLECTING SIGN

Application filed October 23, 1929, Serial No. 401,738, and in Austria January 24, 1929.

Applications have been filed in Austria on the 24th January, 1929, and in Austria on the 22nd July, 1929.

The present invention relates to a light reflecting sign adapted preferably for the use in daylight. The light reflecting sign according to the invention comprises two plates, a front plate and a back plate. The front plate is provided like a stencil with letters cut out thereof or with transparent letters. The back plate disposed directly behind the front plate shows mirrored pyramidal embossments, whose reflecting surfaces are directed to the front plate or stencil.

15 The preferred embodiments of the invention are illustrated in the accompanying drawing, in which—

Fig. 1 is a front view of one embodiment of the invention.

20 Fig. 2 shows a section taken on line $a-b$, Fig. 1.

Figs. 3 and 4 show front views of two further embodiments of the invention.

25 Fig. 5 is a section taken on line $c-d$, Fig. 3.

Fig. 6 is a section taken on line $e-f$, Fig. 4.

Referring to Fig. 1 the front plate 1 of the light reflecting sign is opaque and provided with letters 2 cut out thereof like of a stencil. The letters may also be formed of transparent material. The front side of the back plate 3 is provided with series of mirrored elements 4. These elements are shaped according to the invention as triangular pyramids. One side m of these pyramids is inclined steeply towards the surface of the plate 3, and much shorter than each of the other sides n, o . This form and arrangement of the three sides m, n, o of the mirrored pyramids has the effect to restringe 35 as much as possible the shadows caused by the side m , the long reflecting sides n, o amplifying simultaneously the luminescent effect of the sign.

In the embodiment of the invention illustrated by Figs. 3 and 5 the mirrored triangular intermediate fields z between the pyramidal elements of the back plate 3, are inclined backwards so as to reflect the rays in a more flat direction to the observer. By 40 this arrangement the reflecting sign appears

luminescent not only for observers to the right and to the left hand of the sign but also for observers standing exactly in front of the sign.

In the embodiment of the invention illustrated in Figs. 4 and 6 the mirrored pyramids of one horizontal row are disposed on the upperside of the intermediate fields of the next row, so as to offer a kind of zig-zag arrangement. Further in this embodiment 55 only an inner triangular portion u of each intermediate field z is inclined backwards and this inclined portion forms a triangle p, q, r being smaller than the full intermediate field I, II, III. The small stripes between 60 the corresponding parallel edges of an inner triangle p, q, r and the field I, II, III prevent a direct abutting of the embossed pyramids and the inclined intermediate fields. By this arrangement together with the zig-zag 65 arrangement of the pyramid rows the appearance of continuous shadow-lines is avoided.

I claim:—

1. Light reflecting sign composed of a 75 front plate with transparent letters and a back plate arranged behind the front plate and provided on its front side with mirrored triangular pyramids one side of each pyramid being inclined steeply towards the back plate 80 and much shorter than each of the two other sides.

2. Light reflecting sign composed of a front plate with transparent letters and a back plate arranged behind the front plate 85 and provided on its front side with mirrored triangular pyramids in zig-zag arrangement, one side of each pyramid being inclined steeply towards the back plate and much shorter than each of the two other sides and 90 triangular light reflecting fields on the back plate enclosed by the pyramids.

3. Light reflecting sign composed of a front plate with transparent letters and a back plate arranged behind the front plate 95 and provided on its front side with mirrored triangular pyramids in zig-zag arrangement, one side of each pyramid being inclined steeply towards the back plate and much shorter than each of the two other sides and 100

triangular light reflecting fields on the back plate enclosed by the pyramids and inclined backwards.

4. Light reflecting sign composed of a front plate with transparent letters and a back plate arranged behind the front plate and provided on its front side with mirrored triangular pyramids in zig-zag arrangement, one side of each pyramid being inclined steeply towards the back plate and much shorter than each of the two other sides, triangular light reflecting fields on the back plate, enclosed by the pyramids forming smaller triangular fields inclined backwards.

10 15 In testimony whereof I affix my signature.
HUGO BRUCKNER.
